UNITED STATES PATENT OFFICE.

WILLIAM J. MCINTYRE, OF HARTFORD, CONNECTICUT.

CASTER.

1,206,009.

Specification of Letters Patent. Patented Nov. 28, 1916.

Application filed August 10, 1915. Serial No. 44,676.

To all whom it may concern:

Be it known that I, WILLIAM J. MCINTYRE, a subject of the King of Great Britain, residing at Hartford, in the county of Hartford and State of Connecticut, have invented certain new and useful Improvements in Casters, of which the following is a specification.

This invention relates to casters.

10 Among the objects of the invention is the provision of an article of this character having simple and effective means by which the same can be securely held within a socket and by which the necessary yet limited movement of the branches of a yoke-like frame member can be insured.

15 The device possesses other features of novelty and advantage which with the foregoing will be stated at length in the following description wherein I will set forth in detail that one of the several convenient forms of embodiment of the invention which I have selected for illustration in the drawings accompanying and forming part of the 20 present specification. I do not restrict myself to this particular disclosure; I may depart therefrom in several respects within the scope of the invention defined by the claims following said description.

25 Referring to said drawings: Figure 1 is a longitudinal section of the leg of a piece of furniture, equipped with a caster involving the invention, the caster being in elevation. Fig. 2 is an elevation of the 30 caster removed from said leg. Fig. 3 is a view as seen from the right in Fig. 2. Fig. 4 is a horizontal section on the line 4—4 of Fig. 2, looking in the direction of the arrow. Figs. 5 and 6 are developed views 35 of blanks for the main and auxiliary frame members.

40 Like characters refer to like parts throughout the several views.

The wheel 2, the horn 3, the pintle 4 and 45 the disk 5 may be of any suitable nature; for instance practically like the corresponding parts shown in Letters Patent No. 1,029,705 granted to me June 18, 1912 and to which reference may be had. The disk 50 5 is centrally enlarged to fit within the socket 6 in the leg 7 of a piece of furniture or the like in connection with which a caster of the present or other kind is usable. This disk supports the leg or its equivalent 55 and centers the caster therein.

The holding means in the organization

shown comprises a main frame member as 8 and an auxiliary or supplemental frame member as 9, the latter in the present case, constituting a base for the former and both 60 can be made in an inexpensive and ready manner from sheet metal, as will herein-after more particularly appear. The main frame member 8 is approximately in the form of a yoke or of an inverted U, the 65 sides or branches thereof being normally or initially parallel which is the preferred construction. An advantage follows this relation in that the bodies of said sides do not come into contact with the wall of the 70 socket 6 as the caster is inserted into or removed from said socket. I find that where the sides or branches of a yoke like frame member diverge on downward or outward angles, said bodies come into contact 75 with the outer marginal portion of the socket or leg when the caster is introduced into said socket, the consequence being that the leg especially if it be of metal, will dig into the frame member. In addition to 80 this where the sides are of the angular disposition mentioned it is difficult and sometimes impossible to introduce the frame member into the socket. By making the sides of the frame member parallel in the 85 manner referred to, I can freely and readily pass said frame member into and as easily remove it from a socket. Moreover I can secure the maximum holding effect by having the legs initially in parallelism or practically so. From this it will be inferred that the frame member 8 is resilient. The bodies 90 of the sides of said frame member, however, as will be obvious do not directly engage the wall of the socket, said sides having projections or lugs which properly subserve 95 this function. The transverse portion of the main frame member 8 is approximately centrally perforated to receive the outer portion of the pintle 4, the latter being 100 headed or expanded over the outer surface of said transverse portion to aid in holding the parts assembled. The projections or lugs of the sides of said main frame member 8 will be hereinafter more particularly 105 described.

The auxiliary or supplemental frame member 9 has a substantially central hole or perforation to receive the pintle 5 and also has a bearing upon the central raised 110 or upset portion of the disk 5. Said auxiliary frame member preferably has a suit-

able interlocked connection with the main frame member such connection being of such character as to permit a certain amount of free movement of the sides of the main frame member, this movement being limited in a positive manner as will hereinafter more particularly appear. The body of the auxiliary frame member 9 has at its ends the upstanding or vertical flanges or wings 10 the necks 11 extending horizontally inward from these flanges or wings and being alined. At the inner ends of the necks 11 are transverse or T heads 12 presenting suitable stops to arrest the movement of the sides of the main frame member 8 after said sides have been contracted a predetermined yet comparatively limited distance. The sides or branches of the frame member 8 have slots 13 extending upward a short distance, from the lower edges thereof, the purpose of these slots or notches being to receive the necks or reduced portions 11.

It is an easy matter to assemble the two frame members after they have been formed up in a manner that will hereinafter appear. It is simply necessary to slightly contract the sides of the main frame member 8, slip the necks or reduced portions 11 into the respective slots 13 and then free said sides when the latter will at once spring against the flanges or wings 10 into their virtually parallel relation. If the other parts of the caster are connected together the pintle will then be passed through the coaxial or registering holes in the two frame members and headed at its upper end as already explained.

The sides or branches of the main frame member 8 as shown, are longitudinally slit 40 and the stock at opposite sides of the slits is expanded or bowed outward to form projections or lugs 14 which as shown are directly opposite each other. It is these projections or lugs which by engaging the wall of the socket 6, retain the caster in position. The said projections are between their ends preferably flattened as at 15, the flattened surfaces diverging downward, the result being that the projections together taper upward. Owing to the fact that the outer sides of the lugs are flattened in the manner set forth it is an exceedingly simple matter to introduce the caster into the socket 6 or its equivalent, this condition being further aided by the fact that the outer surfaces of said projections diverge downward. While there is naturally some resiliency in said projections I do not rely upon this to hold the caster in place but primarily utilize the main frame member 8 for this purpose. There is as I observe some resiliency in the projections and in a measure they aid in attaining the desired object. The main holding, however, is done by the sides of the main frame member 8. It will be noted that

the ends of the projections 15 are integral with the sides or branches of the main frame member 8. I have mentioned that said sides are normally substantially in parallelism. It will be clear therefore that if the caster be introduced into the socket 6, the projections 14 will engage the wall of said socket and as the caster is pushed home and as the flattened faces of said projections ride along the wall of the socket the sides of the frame member 8 are caused to approach each other or to be contracted and thus exert a powerful influence or reaction against the projections to thrust the latter solidly and substantially against said wall, the thrust in fact being practically at right angles to the longitudinal axis of the frame member.

In Fig. 5 I illustrate a suitable blank 16 from which the main frame member can be formed up while Fig. 6 is in view representing a convenient blank 17 from which the auxiliary frame member can be formed up. The blank 16 can be longitudinally slit as at 18 and the stock at opposite sides of the slits punched out to form the projections to which I have referred while the blank 16 can be bent on itself along the transverse parallel dotted lines 19 to produce the yoke like frame member 8. The blank 17 can be folded along the parallel lines 21 to produce the wings or flanges 10 and then the neck or reduced portions 11 with their T heads can be bent at right angles to the wings or flanges.

In some cases the frame member 8 can be associated with the other elements of the caster in a manner different from that shown and described.

What I claim is:

1. A caster comprising a horn provided with a wheel and with a pintle, and a yoke-like resilient member connected with and straddling the pintle, the branches of the yoke-like member being flat, freely movable inwardly and outwardly and having outwardly extending projections on their outer faces between the sides thereof, said projections being cut from said branches and their ends being integral with said branches, the outer surfaces of the projections diverging downwardly and said projections acting to space said branches from the wall of a socket into which said yoke-like resilient member is introduced.

2. A caster comprising a horn provided with a wheel and with a pintle, a yoke-like resilient frame member connected with and straddling the pintle the sides of the said frame member having exterior holding projections, and an auxiliary frame member perforated to receive the pintle, the auxiliary frame member being provided with upstanding flanges interlocked with the sides of the main frame member and provided

with means for limiting contracting movement of said sides.

3. A caster comprising a pintle, a main frame member of yoke-like form and resilient, connected with and straddling said caster, the sides of said frame member being approximately in parallelism and being provided with integral outwardly-extending projections on the exterior thereof, an auxiliary frame member perforated to receive said pintle and provided with upstanding

flanges equipped with inwardly-extending necks having T heads, said sides being notched in their lower edges to receive said necks.

15 In testimony whereof I affix my signature in presence of two witnesses.

WILLIAM J. McINTYRE.
